PANEL FOR USE IN PHOTOGRAPHING
MOVIE TITLES AND THE LIKE

Ernest R. Clark, La Verne, Calif.

Application November 1, 1949, Serial No. 124,927

2 Claims. (Cl. 95—85)

1

My invention relates to a device for use in photographing titles for moving pictures, and the like.

A primary object of the invention is to provide a highly simplified unitary device for holding strips or plates of lettering comprising a movie title, or the like, forwardly of a source of light, so that a movie camera may be focused upon the lettering, for photographing it.

A further object is to provide a panel having a translucent pane therein to permit the passage of light, and means to support lines of lettering adjacent to the pane, so that each line of lettering may be adjusted longitudinally independently of the other lines.

A further object is to provide a novel lettering plate or strip having a transparent end portion or overlap, so that the individual letters of the words comprising the movie title may be adjusted, whereby the precise spacing of letters is obtainable.

A further object is to provide a panel for supporting the lettering strips in proper position, relative to a source of light and a camera, and including separate elongated longitudinally adjustable channels having transparent panes, arranged adjacent to the translucent pane of the panel.

A still further object is to provide a device of the above mentioned character which is compact, sturdy, neat and attractive in appearance, and relatively cheap to make.

Other objects and advantages of my invention will be apparent during the course of the following descriptions.

In the accompanying drawings, forming a part of this application, and in which line numerals are employed to designate like parts throughout the same,

Figure 1 is a perspective view of a device for use in photographing movie titles, and embodying my invention,

Figure 2 is a vertical section taken on line 2—2 of Figure 1,

Figure 3 is a rear side elevation of a panel removed,

Figure 4 is a side elevation of a letter mounting channel removed,

Figure 5 is a side elevation of separate lettering strips or inserts removed, and,

Figure 6 is a fragmentary side elevation showing the relationship of one letter mounting channel to the translucent pane of the panel.

In the drawings, where for the purpose of illustration is shown a preferred embodiment of

2

my invention, the numeral 10 designates an elongated flat horizontal support or base panel, upon which is mounted an upstanding electric light bulb 11, arranged near one end of the base panel.

5 A suitable movie camera 12 is mounted upon the base panel 10 and spaced longitudinally of the light bulb for a substantial distance, and preferably having its lens in alignment with the light bulb.

10 Rigidly mounted upon the base panel 10, between the light bulb 11 and camera 12 is an upstanding flat rectangular vertical panel 13, which may be somewhat wider than the base panel 10, so that it projects outwardly laterally of the

15 camera, upon both sides of the camera for a substantial distance. The vertical panel 13 is arranged much closer to the light bulb 11 than to the camera 12, and is spaced slightly forwardly of the light bulb. The panel 13 is provided with

20 a large rectangular opening 14, which is elongated transversely to extend for substantially the entire width of the panel. The opening is arranged near the vertical center of the panel and its center is in alignment with the center of the

25 light bulb 11 and with the axis of the camera lens, as shown. Rigidly mounted upon the rear side of the panel 13, adjacent to the top and bottom longitudinal edges of the opening 14 are transversely extending elongated horizontal retaining strips or bars 15, the inner opposed longitudinal edges of which are arranged flush with the upper and lower longitudinal edges of the rectangular opening 14, Figure 2. Formed in the rear face of the panel 13 adjacent to the top and

30 bottom longitudinal edges of the opening 14 are shallow elongated narrow recesses 16 which extend for the entire length of the rectangular opening 14 and beyond the right hand end of the opening 14, Figure 3. A vertical end strip or bar 17

35 is rigidly mounted upon the rear face of the panel 13 adjacent to its left hand end, Figure 3, and this bar 17 abuts the adjacent ends of the retaining bars 15, as shown and has its inner side arranged substantially adjacent to the adjacent

40 end of the rectangular opening 14. The retaining bars 15 overlap the shallow recesses 16 as shown, and a thin elongated rectangular sheet or pane is removably mounted within the recesses 16 and beneath the retaining bars 15, as shown. The pane 18 is arranged adjacent to and is adapted to completely cover the rear side of the rectangular opening 14, and is slidably longitudinally within the recesses 16 beneath the retaining bars 15 so that it can be removed by sliding it toward the right hand end of the panel 13, Figure 3. The

retaining bars 15 have their ends remote from the vertical bar 17 terminating inwardly of the adjacent end of the panel 13, and the shallow recesses 16 extend longitudinally beyond the adjacent ends of the retaining bars for termination at the inner vertical edge of an elongated vertical wedge bar 19, rigidly mounted upon the rear face of the panel 13 at its end remote from the bar 17. The wedge bar 19 has its outer face 20 inclined, as shown in Figure 1 so that the adjacent end of the sheet or pane 18 will slide up and over the inclined face 20 for easy removal from the adjacent end of the panel.

The sheet or pane 18 is thin, as previously stated, and is somewhat flexible. It is preferably formed of some suitable plastic material, and comprises a central rectangular transversely elongated translucent portion 21, provided with vertically equidistantly spaced narrow horizontal elongated opaque stripes 22, which may be formed with black paint, or the like. Near its opposite ends, the pane 18 has large rectangular end portions or strips 23 and 24 which are opaque, and which also may be formed with black paint. The translucent portion 21 is transversely shorter than the opening 14, and is adapted to be centered between the opposite ends of the opening 14, although the entire pane or sheet 18 is adjustable longitudinally beneath the bars 15.

Removably and longitudinally adjustably mounted within the rectangular opening 14, and having their backs slidably engaging the front face of the pane 18, are a plurality of separate elongated horizontal support channels 25. The channels 25 are arranged in vertical edge to edge superposed relation, Figures 1 and 2, and extend horizontally for the major portion of the length of the opening 14, although the channels are somewhat shorter than the opening 14, so that they may be individually adjusted longitudinally within the opening 14. The channels 25 are somewhat longer than the translucent portion 21 of the pane 18, and their opposite ends extend past the opposite ends of the portion 21. The channels 25 are preferably moulded from a suitable mouldable plastic material, and comprise elongated flat bottoms or plates 26, and integral forwardly extending longitudinal sides or retaining flanges 27, which are curved in transverse cross section, Figure 2, so as to converge forwardly. The opposite ends of the channels 25 are open and the channels are straight. The bottoms or plates 26 of the channels have central elongated transparent portions or windows 28, and the end portions 29 of the bottoms 26, at opposite ends of the windows 28 are opaque. The opaque end portions 29 may be formed with black paint, or the like. The window 28 is of the same length as the translucent portion 21 of the pane 18. An elongated wedge block or strip 30 is adapted to enter between the top edge of the opening 14 and the top side of the upper most channel 25, to retain all of the channels within the opening 14. Each channel is longitudinally adjustable within the opening 14, so that different portions of the windows 28 can be brought into registration with the translucent portion 21.

Removably and longitudinally adjustably mounted within the channels 25 are thin rectangular flexible strips or letter inserts 31, preferably formed of photographic film, or similar material. Inserts 31 are opaque and black, but have transparent portions 32 in the form of different letters of the alphabet arranged centrally, as shown. The inserts 31 also have narrow trans-

parent end portions 32, and the end portion 32 of one insert may be overlapped by the opaque portion of the adjacent insert 31, so that the precise spacing desired between the letters can be obtained, through the longitudinal adjustment of the individual inserts 31 in the channels 25. Elongated rectangular opaque inserts or blanks 33 are also provided, for use between different words of the movie title or for spacing letters a greater distance apart than the length of one of the inserts 31. The blanks 33 have transparent end portions or overlaps 34 to facilitate their longitudinal adjustment with respect to adjacent inserts 31.

The necessary number and arrangement of the inserts 31 and blanks 33 are assembled within the channels 25 as shown in Figures 2 and 4, to produce the desired lines of writing contained in a movie title or the like, to be photographed. The inserts 31 and 33 are adjustable within their channels, and each channel 25 is individually adjustable longitudinally. The inserts 31 and 33 may be positioned adjacent to and forwardly of the windows 28, and the channels may be positioned adjacent to and forwardly of the translucent section 21 of the pane 18. With this arrangement, and with the light bulb 11 glowing, light passes through the translucent portion 21, and through the windows 28. It also passes through the transparent letter portions 32, and through any of the overlaps 32 and 34 which are exposed. The opaque portions 23 and 24 of the pane 18, and the opaque portions 29 of the channel, together with the opaque portions of the inserts 31 and 33 will block out the light from the bulb 11. Thus the letters of the words to be photographed are clearly illuminated, and no other illuminated spots show through the panel 13.

The opaque vertically spaced stripes 22 of the pane 18 are disposed so that they overlap substantially the top half of the windows 28 of the channels 25, Figure 6. The lower halves of the windows 28 are exposed to light, forwardly of the translucent section 21. Due to the transverse curvature of the inserts 31 and 33 in assembly, Figure 2, it has been found that the presence of the stripes 22 result in ideal illumination of the words to be photographed by the camera 12.

Adjacent to the top and bottom edges of the opening 14, and rigidly mounted upon the forward face of the panel 13, are opposed horizontal strips or bars 35 and 36, provided in their lower and upper edges respectively with longitudinal horizontal grooves 37 for receiving a transparent alignment screen or mask, not shown. This alignment mask has spaced vertical lines to aid in centering the lines of lettering on the panel 13.

The forward face of the panel 13 may have any desired ornamentation painted or otherwise applied thereto.

It is to be understood that the form of the invention herewith shown and described is to be taken as a preferred example of the same, and that various changes in shape, size and arrangement of parts may be resorted to, without departing from the spirit of the invention or the scope of the subjoined claims.

Having thus described my invention, I claim:

1. A photographic device for use in photographing symbols comprising a panel adapted to be vertically interposed between a light source and a camera, said panel having an opening formed therein and adapted for longitudinal alignment with a light source and a camera,

retainers disposed above and below the opening and mounted transversely on the side of the panel facing the light source, a flexible opaque sheet, having a transparent center portion, slidably mounted in the retainers and covering the opening, means vertically disposed on the panel transversely of the ends of the retainers for releasably retaining the sheet against longitudinal movement within the retainers, channel members disposed transversely of the opening, means for locking said channel members on the side of panel facing the camera and in vertically arranged and superimposed relation, transparent panels formed in the webs of the channels and flexible opaque inserts adjustably and detachably housed in the channel members and having transparent symbols formed thereon.

2. A photographic device for use in photographing symbols comprising a panel adapted to be vertically disposed in front of a light source and having an opening formed therein and adapted for longitudinal alignment with a light source, retainers disposed above and below the opening transversely on the side of the panel facing a light source, a flexible opaque sheet detachably mounted in the retainers and having a transparent opaquely lined center section, fixed bars vertically formed on the panel at the ends

of the retainers for releasably retaining the sheet against longitudinal movement, channel members disposed transversely in the opening, means for locking said channel members on the opposite side of the panel in vertically arranged relation within the opening, said channel members being longitudinally adjustable and having transparent webs and flexible opaque inserts detachably housed in the channel members and having transparent symbols formed thereon, each of said inserts having a transparent side edge adapted to space the inserts apart and said inserts being positioned parallel to the webs of the channel members.
